4,053,685	10/1977	Rowley et al.

FIG. 1 is a top, rear, right perspective view of the claimed design for a battery;
 FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

In the drawings, the sets of parallel lines depict surface shading. The dot-dash broken lines depict the bounds of the claim. The broken lines depict portions of the battery. The broken lines form no part of the claimed design. The unshaded regions within the shaded areas, bounded by broken lines form no part of the claimed design. Portions of the battery not shown in the drawings form no part of the claimed design.
